US0D1061471S

(12) **United States Design Patent** (10) **Patent No.:** **US D1,061,471 S**
Zhang (45) **Date of Patent:** **** Feb. 11, 2025**

(54) **RECORD PLAYER**

(71) Applicant: **Shenyang Kunyao Enterprise Management Co., Ltd.**, Shenyang (CN)

(72) Inventor: **Shu Zhang**, Shenyang (CN)

(73) Assignee: **Shenyang Kunyao Enterprise Management Co., Ltd.**, Shenyang (CN)

(**) Term: **15 Years**

(21) Appl. No.: **29/952,590**

(22) Filed: **Jul. 16, 2024**

(51) LOC (15) Cl. **14-01**

(52) U.S. Cl.

USPC **D14/202**

(57) **CLAIM**

The ornamental design for a record player, as shown and described.

DESCRIPTION

FIG. 1 is a top, front, right side perspective view of a record player showing my new design;

FIG. 2 is a bottom, rear, right side perspective view thereof;

FIG. 3 is a top, front, left side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of an enclosed portion of the record player labeled 10 in FIG. 1;

FIG. 11 is an enlarged view of an enclosed portion of the record player labeled 11 in FIG. 3; and,

FIG. 12 is an enlarged view of an enclosed portion of the record player labeled 12 in FIG. 3.

The dash-dot-dash broken lines enclosing portions of the record player illustrated in enlargements form no part of the claimed design.

1 Claim, 12 Drawing Sheets
